(57) **CLAIM**

The ornamental design for a design for improved weed cutter,
as shown and described.

DESCRIPTION

FIG. 1 is an isometric view of the invention;
FIG. 2 is a front elevational view of the invention of FIG. 1;
FIG. 3 is a side elevational view of the invention of FIGS. 1
and 2, the other side being a mirror image thereof;
FIG. 4 is a rear view of the invention of FIGS. 1-3;
FIG. 5 is a top view of the invention of FIGS. 1-4; and,
FIG. 6 is a bottom view of the invention of FIGS. 1-5.

1 Claim, 5 Drawing Sheets
